UNITED STATES PATENT OFFICE.

JAMES C. PHELPS, OF SPRINGFIELD, MASSACHUSETTS.

CONNECTOR FOR ELECTRIC CONDUITS.

1,122,600.

Specification of Letters Patent. Patented Dec. 23, 1914.

Application filed June 18, 1913. Serial No. 774,486.

To all whom it may concern:

Be it known that I, JAMES C. PHELPS, a citizen of the United States, residing at Springfield, in the county of Hampden and State of Massachusetts, have invented certain new and useful Improvements in Connectors for Electric Conduits, of which the following is a specification.

This invention relates to improvements in connectors for electric conduits.

An object of the invention is to provide means to connect the ends of the conduits together in a rigid manner.

A further object is to provide a connector, through which the electric cables can be easily drawn without injury, and at the same time provide a connector which will afford ample space for the cables.

A further object is to provide a connector which will permit the conduits to be thoroughly grounded.

Referring to the drawings,—Figure 1 is a plan view of the base portion of the connector with the cap removed, and showing the ring or rib at the ends of the same and against which the bushing on the ends of the conduit rest. Fig. 2 is a sectional detail view of the end-cap-member. Fig. 3 is a plan view of the end cap-member. Fig. 4 is a plan view of the cap-member. Fig. 5 is a transverse sectional view of the base-member on the line 5—5 of Fig. 1 showing the ledge on which the cap-member rests when in place. Fig. 6 is a sectional view on the line 6—6 of Fig. 4, showing the form of the same. Fig. 7 is a view showing the base-member of the connector rigidly secured to the two ends of the conduit and with the cap-member (shown in Fig. 4) removed ready for the drawing in of the cables. Fig. 8 is a view similar to Fig. 7 but with the cap secured in place, and Fig. 9 is a sectional detail view of an end of the conduit showing the bushing in place, the section being taken on the line 9—9 of Fig. 8.

Referring to the drawings in detail,—10 designates the base-member of the connector that is formed with the ledge-positions 11 to receive the edges 12 of the cap-member 13.

14 designates ears by means of which the cap-member 13 is secured to the base-member by passing bolts through the ears 15 of the cap.

The end of the base-member is formed with an inturned lip or rib 16,—the inter-

nal diameter of this rib being equal to the external diameter of the conduit 17, and its threaded end is passed therethrough, as shown in Figs. 7, 8 and 9.

18 designates a bushing that is threaded 60 onto the inner ends of the conduit and when in place engages the inner side of the rib 16, as shown in Figs. 7, 8 and 9.

19 designates end-cap-members to rigidly 65 secure the conduits 17 to the base-member prior to the securing of the cap or cover 19' in place. These cap-members are formed with an inturned rib 20 that is adapted to register with the rib 16 of the base-member when in place and against which it is engaged by the bushing 18 when assembled.

The end cap-members 19 are provided, with a lip or projection 21 which receives the end portion 22 of the cap 19' when assembled, as shown in the detail sectional 75 view in Fig. 9. A set-nut 23 is threaded onto the end of the conduits 17 and is designed to engage the outer ends or sides of the ribs 16 and 20 of the base and end cap-members, respectively, as shown in Figs. 7, 80 8 and 9.

Referring now to the manner in which the connector is assembled and used: The set-nuts 23 are first threaded onto the ends of the conduits 17 that are to be connected together. Next, the bushings 18 are screwed onto the ends of the conduits 17, as shown. The base-member 10 is then put in place on the ends of the conduits 17 with the bushings 18 engaging the inner sides 16' of the 90 ribs 16 and the set-nuts 23 the outer sides of the ribs 16. The end caps 19 are next secured in place by means of the ears 19' and the ears 14' of the base-member. The set-nuts 23 are now turned tightly against 95 the outer sides of the ribs 16 and 20 of the base and cap-members, respectively. The base-member 10 of the connector is now rigidly secured to the conduits and with the cap 19' removed or not in place. The cables 100 are now ready to be drawn into the conduits and placed in the connector. This invention is especially useful where large and heavy cables are to be drawn into the conduits and around short bends therein. Rig- 105 idly connecting the ends of the conduits 17 together by means of the base-member 10 (and before the cap-member 19' is secured in place) it enables the operator to easily draw a length of the cable through the con- 110

116

duit by grasping the cable at this uncovered point. The cables can then be grasped at another point in the conduit and the slack taken up at the connector point in the system of wiring.

The construction of my connector is such as to provide a full unrestricted opening therethrough, the diameter of which is indicated at 10' in Fig. 7. Thus an opening of larger diameter than that of the conduits 13 17 is available for use in pulling in or splicing cables. The flange 10² is formed flush with the exterior wall of the base-member of the connector and the interior surface of the 15 connector, when the cap 19' is in place, is smooth and unobstructed, thereby furnishing plenty of room for the cables without any crowding, which is a very important feature in conduit construction, as it enables the cables or wires to be inserted without 20 any danger of tearing the insulation from the wires and causing a short circuit. The invention also enables a ready inspection of the cables to be made at the bends by 25 simply removing the cap 19' without disturbing the base-member 10 and its attachment to the conduits. It also affords plenty of space for splicing.

Another important feature of this invention is that it enables a thorough ground or 30 metallic connection between the ends of the conduits to be made by means of the ribs, bushing and set-nuts construction, which furnishes the means to attach the base-piece 35 to the ends of the connector, as described.

It is to be distinctly understood that I do not limit myself to the arc-shaped form 40 shown in the drawings, as the connector may be in the form of a T, or cross-shaped, or it may be straight, as convenience requires.

What I claim, is,—

1. A connector construction for electric conduits, comprising in combination, a base-member, an inturned rib formed at its opposite ends, a conduit, bushings on the oppositely disposed inner ends of the conduits and engaging the inturned rib at each end of the connector, set nuts on the conduit and designed to bear against the outer ends of 45 the ribs to rigidly secure the connector and conduits in place, end caps each formed with a rib to register with the ribs on the base-member, means to secure the end-caps in place, a cap-member located between the end-caps to close the connector, and means to removably secure the cap-member in place.

2. A connector for electric conduits, comprising a base-member substantially semi-circular in cross-section, an inturned rib at 50 its ends, a flange or rib formed on the edges of the base-member, end-cap-members, inturned ribs formed therewith and adapted to register with the inturned ribs of the base-member, means to secure the end-cap-members to the base-member, a cap-member

located between the end-cap-members and within the flanges on the edges of the base member, and means to secure the cap-member to the base-member.

3. A connector for electric conduits, comprising a base-member the ends of which are formed with inwardly-projecting rib-portions designed to secure the ends of the conduits thereto, end-cap-members formed with inturned ribs and adapted to register with 70 said ribs on the base-member, means to secure the end-cap-members to the base-member, whereby when the ends of the conduits are provided with a set-nut and end-bushing, respectively, and located on opposite surfaces of the registering ribs of the base and end-cap-members, the ends of the conduits may be secured to the connector and with the space between the end-cap-members left 75 open to draw in the cables, as described, a cap-member, and means to secure the same to the base-member.

4. A connector for electric conduits, comprising a base-member formed with ribs at its extreme end-portions, end-cap-members formed with ribs adapted to register with the ribs of the base-member, means to secure the cap-members to the base-member, flanges on the edges of the base-member, and a cap or cover-member located between the 90 end cap-members and within the edge flanges, whereby when the conduits are secured to the base-member the cap-member may be removed to permit the cables to be drawn in as described.

5. A connector for electric conduits, comprising a base-member, inwardly projecting rib-portions integral therewith and designed to secure the ends of the conduits thereto, end-cap-members formed with inturned ribs 105 and designed to register with said ribs on the base-member, said end cap members being spaced from one another on the base member leaving an open space therebetween, means to secure the end-cap-members, to the base-member, whereby when the ends of the conduits are provided with a set-nut and an end-bushing spaced from each other, as described, and located on the opposite inner and outer surfaces of the registering ribs of 110 the base and end-cap-members, the ends of the conduits may be rigidly secured to the connector, leaving a large opening between said end cap members available for pulling 115 in cables.

6. A connector for electric conduits comprising, in combination, a semi-circular base-member, a rib at the end thereof, a semi-circular end-cap member, a rib integral therewith, means to secure the end-cap member to the base-member, whereby a conduit 120 having spaced nuts on its end portion may be rigidly secured to the base-member, as described.

7. A connector for electric conduits com-

prising, in combination, a base-member, a rib at the end thereof, an end-cap-member, a rib integral therewith, means to secure the end-cap member to the base-member, a flange on the said base-member and spaced away from its inner surface to provide a ledge, a cap-member designed to engage said ledge to form a closed connector, as described.
